(57) **CLAIM**

The ornamental design for a wheel rim, as shown and described.

DESCRIPTION

FIG. 1 is a perspective view of a wheel rim, illustrated with a rotor, showing the new design;

FIG. 2 is a perspective view of the wheel rim, illustrated without a rotor, showing the new design; and,

FIG. 3 is a front elevation view thereof.

The broken lines shown in the drawings are for the purpose of illustrating portions of the wheel rim and forms no part of the claimed design. In the FIG. 1 drawing, the rotor illustrated in broken line forms no part of the claimed design.

1 Claim, 3 Drawing Sheets

FIG. 1

FIG. 2

FIG. 3
